COMBINED GAME BOARD AND DICE AGITATOR
George A. Hermann, 1013 Pape Ave.,
Fort Wayne 7, Ind.
Filed May 9, 1961, Ser. No. 108,950
1 Claim. (Cl. 273—136)

This invention relates to a game board, and has as its primary object the provision of a game board which may be suitably surface marked in any desired manner for the playing of any desired game, wherein there is provided a centrally located dome, which contains a die or dice, together with mechanical means for agitating the die or dice from any one of a plurality of selected positions about the board.

A further object of the invention is the provision of a device of this character wherein the bottom of the glass dome is provided with a diaphragm which is selectively struck by one or more of a plurality of hammer members, each of the hammer members being actuated from a selected position around the periphery of the board.

A further object of the invention is the provision of a game board of this character wherein the impact is delivered off center of the diaphragm, so as to impart spin or rotative movement to the die or dice contained in the dome.

Still another object of the invention is the provision of a game board of this character which is sturdy and durable in construction, reliable and efficient in operation, and relatively simple and inexpensive to manufacture.

Other objects will in part be obvious and in part be pointed out as the description of the invention proceeds and shown in the accompanying drawing wherein:

FIGURE 1 is a top plan view of one form of game board constructed in accordance with the instant invention.

FIGURE 2 is an end elevational view of the device of FIG. 1.

FIGURE 3 is an enlarged sectional view taken substantially along the line 3—3 of FIG. 1 as viewed in the direction indicated by the arrows.

FIGURE 4 is a bottom plan view of a portion of the actuating mechanism, on an enlarged scale; and

FIGURE 5 is an enlarged sectional view taken substantially along the line 5—5 of FIG. 1 as viewed in the direction indicated by the arrows.

Similar reference characters refer to similar parts throughout the several views of the drawings.

Having reference now to the drawings in detail, the game board of the instant invention is generally indicated at 10 and comprises a top or playing surface 11 which is surrounded by a plurality of depending flanges 12, which support the underside of the playing surface a distance from the supporting surface T, which may comprise a table top or the like, and serve to permit the accommodation of suitable mechanism to be hereinafter described. The top 11 of the game board, which may be rectangular, or any other desired shape to accommodate four or more players, may be ornamented in any desired manner, and may be provided with a plurality of indentations 13 for the reception of marbles or other playing pieces, the indentations being arranged in a predetermined pattern along which the playing pieces may be moved. If desired, a different color may be employed for each player, and since an infinite variety of patterns may be provided, as well as an infinite variety of rules of play, no further description need be given other than to say that the movement of pieces along the predetermined paths outlined by the openings 13, which, if desired, may be omitted, and be supplanted by other suitable space

2

indicia, is determined by the spots on a die or dice 14, which are mounted on a diaphragm 15, interiorly of a bore or opening 16 in the center of the board. The opening 16 is closed by a glass dome 17 which has a concave top 17a adapted for the reception of a marble 17b in accordance with the playing rules of the game, or other transparent dome through which the die or dice may be readily observed. The arrangement is such that when a die or dice are moved in a manner to be more fully described hereinafter, by impact against the diaphragm 15, a player moves a piece or pieces a selected number dictated by the numeral appearing on the uppermost face of the die.

While dice are herein described in conjunction with the game of the instant invention, it is to be understood that other cubes bearing pictorial representations upon their various surfaces may be employed, if desired.

Each flange 12 is preferably provided with a centrally positioned opening or bore 20 through which extends a rod 21, the end of the rod being provided with an operating knob 22 exteriorly of its associated flange 12 by means of which the same may be rotated. The opposite end of each rod 22 is provided with a pin 23 extending diametrically therethrough, which pin when rotated is adapted to engage a leaf spring 24 which is mounted on a suitable block or plate 25, as by means of rivets 26, the plate 25 being supported from a central annulus 27 which surrounds the underside of the diaphragm 15, the annulus being provided with a depending flange 28 to which the plates 25 are affixed, there being one plate 25 and an adjacent rod provided for each side of the board, in the illustrative embodiment herein shown, 4. Suitable screws 30 secure the annulus 27 to the underside of the top 11 of the game board.

The end of each spring 24 carries a screw or bolt 35 having a head 36 which is positioned beneath the diaphragm 15, and serves as a hammer thereagainst. Oppositely disposed lock nuts 37 and 38 on opposite sides of each spring serve to hold the screws 35 in position.

As is best seen in FIG. 4, the ends of the several springs 24 are overlapped so that each screw head 36 is off center with respect to the center of diaphragm 15, so that any impact thereon will cause the die or dice 14 positioned on the diaphragm to tumble from an off center position thus changing its spots. Obviously, in playing the game the impact may be provided by any player by simply rotating the knob 22, which through the rod 21 and the pin 23 depresses the spring 24 associated therewith to the position shown in the right hand side of FIG. 3, whereupon further rotation will release the spring towards the same to sharply impact the associated head 36 against the underside of the diaphragm to jostle with die and cause the same to change position.

Obviously, a wide variety of playing rules may be utilized, and a variety of games dependent on the turn of a die may be played.

From the foregoing it will now be seen that there is herein provided an improved game board which accomplishes all of the objects of this invention and others, including many advantages of great practical utility and high entertainment value.

As many embodiments may be made of this inventive concept, and as many modifications may be made in the embodiment hereinbefore shown and described, it is to be understood that all matter herein is to be interpreted merely as illustrative, and not in a limiting sense.

I claim:

A game comprising, in combination, a playing surface having portions defining a centrally disposed opening therein, a depending flange to support said playing surface, a diaphragm secured beneath the opening in said

playing surface, a transparent dome closing the opening, a die supported on said diaphragm, an annulus surrounding said diaphragm, radially extending plates secured to said annulus and being substantially parallel to said playing surface, leaf spring members each secured at one end to a corresponding one of said radially extending plates, the free ends of each of said leaf spring members terminating in underlying spaced relation to said diaphragm and offset from the center thereof, a bolt having a head portion fixed in the free end of each of said leaf spring members at right angles thereto, the head portion of each bolt disposed adjacent said diaphragm, rotatable rods each having one end extending through said depending flange and each terminating at their other end adjacent one of said leaf spring members, a diametrically extending pin through each rod at the end adjacent the leaf spring mem-

5

ber, said rods selectively rotatable to cause engagement of said pin with said leaf spring member to cause flexure thereof away from said diaphragm, said pin disengageable from said leaf spring member upon further rotation of said rod to cause the spring member to rebound toward said diaphragm whereby the head portion of the bolt will strike the same to cause the die supported thereon to roll.
